UNITED STATES PATENT OFFICE.

SAMUEL R. KRAMER, OF PHILADELPHIA, PENNSYLVANIA, ASSIGNOR TO KRAMER WEB MANUFACTURING COMPANY, OF PHILADELPHIA, PENNSYLVANIA, A CORPORATION OF PENNSYLVANIA.

BRONZING ATTACHMENT FOR PRINTING-PRESSES.

No. 829,074.

Specification of Letters Patent.

Patented Aug. 21, 1906.

Application filed September 12, 1905. Serial No. 278,142.

To all whom it may concern:

Be it known that I, SAMUEL R. KRAMER, a citizen of the United States, residing in Philadelphia, Pennsylvania, have invented a 5 Bronzing Attachment for Printing-Presses, of which the following is a specification.

My invention consists of a novel combination and construction of apparatus for applying a bronzing-powder or similar substance 10 to a continuous web of sheet material, such as paper, after the same has been passed through a printing-press or has been otherwise properly prepared for bronzing.

More especially the invention consists in a 15 bronzing attachment particularly applicable to presses of the Gordon type and of such construction that it operates upon a continuous web of material between the time that the said web receives an impression from the 20 press and the time when it is slit or cut into a number of pieces.

One object of the invention is to provide an attachment of the character above noted which shall be applicable to printing-presses 25 without requiring material change in their construction and which, while being efficient and reliable in operation, shall be relatively inexpensive to construct and place in position.

30 It is further desired that the device shall so operate as to be relatively economical in its use of bronzing material.

These objects I attain as hereinafter set forth, reference being had to the accompanying drawings, in which—

Figure 1 is a side elevation of a printing-press, illustrating my invention as applied thereto. Fig. 2 is a plan view, on a larger scale than Fig. 1, showing the preferred arrangement of the parts comprising my bronzing attachment. Fig. 3 is a sectional elevation taken on the line 3 3, Fig. 2. Fig. 4 is a side elevation of a portion of the mechanism employed for operating the bronzing-brushes.

40 Fig. 5 is a detail sectional elevation illustrating the connection between certain of the parts of the device shown in Fig. 4, and Fig. 6 is a side elevation of the device for periodically jarring the feeding mechanism for the 45 bronze-powder.

In the above drawings, A is a framework supported upon the body structure of a print-

ing-press of the Gordon type (shown in dotted lines at Q) in such position that a continuous web of paper after passing over the bed and before its engagement by the wheels a for longitudinally cutting said web into a number of strips will be compelled to pass through said frame. As will be understood by those skilled in the art, such a press includes a relatively large gear-wheel a' , to the face of which is attached one end of a connecting-rod a^2 for oscillating that portion q' of the press upon which the platen is carried.

The frame A of the bronzing attachment is 65 preferably made in box form and provided with a suitable guide-roller b^4 , over which passes the continuous web of paper after it leaves the bed of the press. From this roller said web passes through the box-like frame 70 and between a pair of rollers b and b^2 , after which it is drawn between any desired number of pairs of slitting-wheels a of the well-known form, whereby it is divided into a number of longitudinally-extending strips. 75 In its passage through the frame A the paper web is for some distance supported upon a smooth flat table or guiding-surface c , above which extends a transverse shaft C, carrying arms c' , whose ends in the present instance 80 are turned up for the reception of perforated bars d , fixed to the backs of brushes D, which brushes rest upon that portion of the web of paper supported by the surface c , there preferably being small weights d' carried on said 85 brushes, by which their pressure on the paper may be increased.

Longitudinal motion is given to the shaft C, and hence to the brushes D, through a bell-crank lever E, one arm of which is slotted at e , 90 as shown in Fig. 5, to receive a pin c^3 , projecting from the collar c^2 , fastened to the shaft C. The second arm of the lever E is provided with a substantially spherical end which is engaged by one end of a link e' , whose opposite end is journaled on a crank-pin a^3 , projecting from the face of a pinion a^4 , which meshes with the gear-wheel a' .

In front of and above the brushes D is a hopper G, suitably supported on and extending across the frame A and having through its lower portion a revoluble shaft or feed-roller g . Between this roller and the surface of the paper web a^5 is a longitudinally-ex-

tending structure g' , forming the bottom of the hopper and provided with any desired number of feed-holes g^3 , extending through it.

There are in the feed-roller g a number of 5 groups of recesses or depressions g^2 , so placed that each group lies in the same plane as one of the passages g^3 in the bottom g' of the hopper G. The amount of material passing through the openings g^3 in this bottom structure may be regulated by means of set-screws 10 g^4 , it being possible by moving said screws in or out to vary the cross-section of a portion of the respective passages. The feed-roller g in the hopper is turned under operating 15 conditions by means of a sprocket g^5 , placed upon a portion of said shaft which extends outside of the framework A, it being understood that said sprocket may be and usually is driven from any suitable part of the mechanism 20 of the printing-press, (in the present instance one of the web-feeding rollers,) which is only operated when the said paper web is to be fed. Said sprocket g^5 is connected by a chain g^6 to a similar sprocket b^5 on the roller b .

Carried in suitable bearings on the frame 25 A and provided with pulley-wheels h and h' are two substantially parallel shafts H and H', on each of which is a cylindrical brush, (indicated by the letters h^2 and h^3 , respectively.) Said shafts are so placed that one of the brushes is in engagement with the upper surface of the paper web while the other brush h^3 is to the rear of the first roller and in such position as to engage the under surface 35 of said web.

Collecting-trays J and J' are, respectively, placed in front and back of the brush h^2 , which, with the brush h^3 , may be made of felt or other relatively soft material for the purpose 40 of removing the surplus bronzing-powder from the paper web. The trays J and J' rest upon guides j and j' , fastened to the sides of the frames A, and each of them has at one end and near its sides angle-pieces 45 j^2 , in each of which is a set-screw j^3 , so placed as to engage the upper ends of the various guideways j and j' . By means of these set-screws the position of the trays or plates J and J' may be adjusted relatively to the brush h^2 . Upon the shaft g outside the frame A is a cam i , placed to act upon a pin i' , projecting from a weighted arm I, pivoted to said frame. As said shaft g is turned the cam causes this arm to be alternately lifted 50 and allowed to drop upon the shaft g , thereby periodically jarring it for a purpose hereinafter noted.

Under operating conditions the recessed feed-roller g is intermittently rotated within 60 the hopper, which is supplied with bronzing-powder, so that the various recesses g^2 in said feed-roller are alternately filled with the powder and caused to empty into the various feed-passages g^3 in the structure g' , forming 65 the bottom of said hopper. Should the

bronze-powder tend to clog said recesses or passages, the successive blows struck the shaft or roller g by the arm I will act to dislodge such accumulation of powder.

It will be understood that under operating 70 conditions various characters or symbols are printed by the press upon the web of paper in the customary way, the printing-ink employed being of a nature particularly fitted to receive bronze-powder and cause it to adhere 75 to the paper web. As said web leaves the printing mechanism it passes under the hopper G, from whence it receives definite quantities of bronze-powder and then moves under the brushes D. As these latter are vibrated from side to side over the web by the combined action of the link e the bell-crank lever E, and the shaft C they not only distribute the bronze-powder over said web, but cause it to be thoroughly rubbed upon the 80 surface thereof, so that the inked portions receive a complete continuous coating of said powder. From these brushes the web passes between the brushes h^2 and h^3 , the former of which, turning in the direction of the arrow 85 in Fig. 3, collects the surplus bronze-powder and deposits it either upon the tray J or upon the tray J', so that the only powder remaining upon said web is that upon the portions thereof to which the ink or adhesive material 90 has been applied. The brush-roller h^3 removes from the under side of the web any particles of bronze-powder which may have accidentally collected thereon during its passage through the box-like frame A. By moving 95 the set-screws g^4 so that they restrict the area of the passages g^3 in the bottom of the hopper the length of time required to deliver the charges of bronze-powder to the web may be varied as desired, it being thus possible to 100 adjust with great nicety the delivery of powder from the hopper. As surplus powder accumulates upon the trays J and J' these are 105 lifted from their guides and emptied into the hopper G.

I claim as my invention—

1. The combination of a bronzing device, means for feeding a web of material through the same, a reservoir having an opening or series of openings for delivering material to the web, a revoluble feed-shaft in the reservoir provided with a recess or series of recesses placed to receive material from the reservoir and deliver the same to the openings thereof, with means for distributing over the web, the material delivered from the reservoir, substantially as described.

2. The combination in a bronzing device, of means for feeding a web of material, a reservoir having in its lower portion a series of 125 openings, a feeding device including a shaft provided with a recess or series of recesses each placed to receive material from the reservoir and deliver the same to one of the openings in the reservoir, with means for 130

turning said shaft, and means for distributing material delivered from the reservoir over the web of material, substantially as described.

5 3. The combination in a bronzing device of a reservoir and means for delivering bronzing material upon a web of material, means for feeding the web to the device, means for distributing over the web the material delivered from the reservoir, a rotary brush for removing the surplus bronzing material from the web, and a receptacle on each side of said brush for receiving material collected thereby, with means for adjusting the distance between the brush and the receptacle, substantially as described.

4. A bronzing device including means for feeding a web of material, a reservoir having an opening for delivering material to the web, 20 a feeding device constructed to receive material from the reservoir and to deliver the same to the opening therein, with means for adjusting the size of said opening, and a device for distributing over the web the material delivered from the reservoir, substantially as described.

5. A bronzing device including means for feeding a web of material, a reservoir for delivering bronzing material to the web, a bar 30 transversely supported over the web, a brush attached to said bar, so as to rest upon the web, a lever having one arm connected to the bar, a link connected to the second arm of the lever, a crank having a pin connected to said link, with means for turning said crank, substantially as described.

6. A bronzing device including means for feeding a web of material, a reservoir having means for delivering powdered material to 40 said web, a brush for distributing said mate-

rial over the web, means for moving said brush including a bar attached thereto, a lever, a collar on said bar having a pin engaging a slot in one arm of said lever, a crank, means for turning the same, and a link connecting the pin of said crank with the lever, substantially as described.

7. A bronzing device including a reservoir for bronzing material having a feeding device consisting of a revoluble receptacle for receiving material from the reservoir and delivering it upon a surface to be bronzed, with means for jarring said receptacle to dislodge material therein, substantially as described.

8. A bronzing device including means for feeding a web of material, a reservoir for bronzing powder having a revoluble feed-shaft provided with a recess or recesses placed to receive powder from the reservoir and deliver the same to the web, with means for distributing said powder over the web, and means for periodically jarring said feed-shaft, substantially as described.

9. A bronzing device including means for feeding a web of material, a reservoir for bronzing powder having a revoluble feed-shaft provided with a recess or recesses placed to receive powder from the reservoir and deliver the same to the web, with means for distributing said powder over the web, a cam 70 on the feed-shaft and an arm operated thereby, and placed to jar said shaft when so operated, substantially as described.

In testimony whereof I have signed my name to this specification in the presence of 75 two subscribing witnesses.
